UNITED STATES PATENT OFFICE.

ISAAC KARPEN, OF CHICAGO, ILLINOIS, ASSIGNOR TO S. KARPEN & BROS., OF CHICAGO, ILLINOIS, A CORPORATION OF WEST VIRGINIA.

UPHOLSTERING-MACHINE.

No. 903,097.

Specification of Letters Patent.

Patented Nov. 3, 1908.

Application filed October 25, 1907. Serial No. 399,188.

To all whom it may concern:

Be it known that I, ISAAC KARPEN, a citizen of the United States, residing at Chicago, in the county of Cook and State of Illinois, have invented a new and useful Improvement in Upholstering-Machines, of which the following is a specification.

My invention constitutes an improvement on the upholstering machine described and 10 claimed in my application No. 390,024, filed August 24, 1907.

My primary object is to provide improved fastener-holding means for use in connection with a machine of the character indicated.

15 The invention is illustrated in the accompanying drawing, in which—

Figure 1 represents a broken sectional view of a mold for a tufting-machine having its presser-board, or follower, equipped with 20 my improved fastener-holding means, and showing a mattress, or pad, in process of formation; Fig. 2, a similar view showing the edge-rail of the mold removed and the covering of the mattress, or pad, turned up 25 for connection with the fasteners; Fig. 3, a perspective view of my improved fastener-clip with an individual fastener-retainer; Fig. 4, a broken edge elevational view of the same; Fig. 5, a broken perspective view 30 of a follower-board equipped with my improved individual fastener-clips, illustrating how the same may be applied to an irregularly-shaped edge; Fig. 6, a broken sectional view showing a modification of the fastener- 35 clip; and Fig. 7, a broken perspective view showing a still further modification.

In the drawing, A represents a mold for a tufting-machine having a bottom A¹ and a removable edge-rail A²; B, the follower, or 40 presser-board, of the mold; and C, individual fastener-clips applied to the edge of the follower.

Each clip C comprises a vertically-disposed fastener-guide c equipped at its upper 45 and lower ends with rearwardly-turned attaching-flanges c¹; and a spring-retainer c² connected with the lower flange. The fastener-guide c is provided with a T-slot c³ open at its upper and lower ends and open 50 at the front of the guide to receive the shank of the fastener, as indicated at c⁴. The spring-retainer c² is attached at its rear end to the rear portion of the lower flange c¹ and its front end projects across the lower

end of the T-slot, as will be clearly understood from Figs. 3 and 4. The flanges c¹ are adapted to embrace the upper and lower surfaces of the follower-board, as illustrated in Fig. 5, and are secured to the follower-board, as by screws c⁵. The head of the 60 fastener c⁶ is received in the T-slot, the shank of the fastener projecting through the open channel c⁴, as clearly illustrated in Fig. 1, the head of the fastener resting upon the retainer c².

D represents a mattress, or pad (inverted during tufting), having an inner fabric (usually canvas) d, an outer covering (usually leather or imitation leather) d¹, and a fringe or flap d². As is known, the margins of these fabrics are preparatorily perforated to receive the fasteners. After the fasteners are entered and clenched, the follower-board may be lifted from the pad, the retainers c² yielding to permit the heads of 75 the fasteners to pass.

In the construction illustrated in Fig. 6, C¹ represents a modified form of my improved fastener-clip, the construction being very similar to the construction already described. In this construction, however, the retainer spring c² is dispensed with, and a shoulder c⁷ is formed at the base of the guide c for the fastener-head to rest upon, the walls of the guide being sufficiently yielding to 85 permit the fastener-head to pass said shoulder when the follower-board is lifted from the pad.

Fig. 7 shows a still further modification, in which C² represents a fastener of the 90 same general construction as those already described. In this construction, the retainer spring c² is dispensed with, and the front wall of the fastener-guide c is equipped at its base with a rearwardly or inwardly 95 turned lip c⁸ upon which the fastener-head may rest. In this construction, the lip and wall of the guide to which it is attached will yield sufficiently to permit the head of the fastener to pass when the follower is lifted 100 from the pad.

The invention is applicable to the follower of any pad-forming machine, regardless of whether or not the tufting operation is performed in the same machine.

It is to be observed that by omitting the fastener-retainer rods which I have heretofore employed and providing individual re-

tainers for the fastener-guides, I not only render it possible to apply my invention to a follower-board having an irregularly shaped edge, but I also render it possible to apply the fasteners closer to the body of the pad, or mattress, than has heretofore been possible.

What I regard as new and desire to secure by Letters Patent is:—

- 10 1. The combination with a follower of a pad-forming machine, of fastener-guides applied to and crossing an edge thereof and constructed with individual fastener-retaining means.
- 15 2. The combination with the follower of a pad-forming machine, of individual fastener-guides applied to an edge thereof and extending perpendicular thereto and equipped with individual fastener retainers, for the purpose set forth.
- 20 3. The combination with the follower of a pad-forming machine, of fastener-guides applied to an edge thereof and extending substantially perpendicular thereto, and indi-

vidual fastener-retainers at the lower portions of said fastener-guides.

4. The combination with the follower of a pad-forming machine, of fastener-guides at an edge thereof extending perpendicular to the follower, and spring-retainers projecting into the path of the heads of the fasteners at the lower end-portions of the fastener-guides.

5. A fastener-clip for the purpose set forth comprising a fastener-guide equipped with attaching means, and a fastener-retainer extending into the path of the head of the fastener, for the purpose set forth.

6. A fastener-clip for the purpose set forth comprising a fastener-guide with a T-shape slot, attaching flanges projecting rearwardly from said guide, and a retainer-spring carried by the lower flange, for the purpose set forth.

ISAAC KARPEN.

In presence of—

K. M. CORNWALL,
R. A. RAYMOND.
